UNITED STATES PATENT OFFICE.

SIDNEY A. MYERS, OF JOPLIN, MISSOURI, ASSIGNOR OF ONE-HALF TO BYRON H. COON,
OF JOPLIN, MISSOURI.

STARTING DEVICE FOR INTERNAL-COMBUSTION ENGINES.

1,115,962.

Specification of Letters Patent.

Patented Nov. 3, 1914.

Application filed July 19, 1912. Serial No. 773,892.

To all whom it may concern:

Be it known that I, SIDNEY A. MYERS, a citizen of the United States, and a resident of Joplin, in the county of Jasper and State of Missouri, have invented certain new and useful Improvements in Starting Devices for Internal-Combustion Engines; and I do hereby declare that the following is a full, clear, and exact description thereof, reference being had to the accompanying drawings, and to the letters of reference marked thereon, which form a part of this specification.

This invention relates to manually operable starting devices for internal combustion engines.

The principal object of the invention is to provide a simple, economical and efficient starting device for internal combustion engines.

A further object of the invention is to provide an improved starting device for internal combustion engines adapted to enable an engine to be cranked or started with facility by manually operated mechanical means adapted to be operated from the driver's seat.

Other and further objects of the invention will appear from an examination of the drawings and from the following description and claims.

The invention consists in the features, combinations, and details of construction herein described and claimed.

In the accompanying drawings—Figure 1 is a plan view of a starting device constructed in accordance with my invention and improvements, showing the outer tubular casing in horizontal section and disclosing the rotary helix or spirally grooved pawl and ratchet operating member for rotating the starter shaft in starting or cranking the engine; Fig. 2, a vertical sectional view, taken on line 2 of Fig. 1 looking in the direction of the arrow, and showing the central tubular outer casing, the starter shaft and the rack and pinion mechanism and helix-operating mechanism in elevation with all of the parts in the position which they would occupy when the starter shaft is first moved longitudinally into position to bring the clutch member on the starter shaft into clutching engagement with the clutch member on the engine shaft, the sliding frame or sleeve and helix-operat-

ing fingers carried thereby being in position to rotate the engine shaft or crank the engine by the movement of said last mentioned parts from the position shown in Fig. 2 to the position shown in Fig. 1; Fig. 3, a view in central longitudinal vertical section, taken through the center of the parts shown in Fig. 1, and showing the parts as they would appear with the starter shaft in clutch out of clutching position, and with the rack and pinion mechanism in such position that the movement of the bottom rack from the position shown in Fig. 3 to the position shown in Fig. 2 will throw the main clutch member on the starter shaft into clutching position; Fig. 4, a central horizontal sectional view, taken on line 4 of Fig. 2 looking in the direction of the arrow, and showing the main clutch members in clutching engagement and the main operating lever and helix-operating fingers at the opposite extremity of their movement from that in which they are shown in Fig. 1, the main operating lever in Fig. 4 being in the position which it would occupy at the beginning of its stroke or movement in rotating the engine shaft or starting the engine; Fig. 5, a transverse vertical sectional view in detail, taken on line 5 of Fig. 3 looking in the direction of the arrow, and showing the helix-operating fingers supported by the sliding sleeve in engagement with the main helix or spiral for rotating the starter shaft, with the main clutch members in clutching engagement, and showing the inner helix or helically grooved sleeve for rotating the starter shaft, during the initial endwise movement of the starter shaft and clutch, and immediately following such endwise movement of said shaft and clutch into clutching position or into engagement with the engine shaft; Fig. 6, a transverse vertical sectional view, taken on line 6 of Fig. 3 looking in the direction of the arrow, and showing the pawls and ratchet mechanism for rotating the starter shaft and the helix-operating fingers for rotating the main or outer relatively large helically grooved tubular member and thereby the pawls and ratchet shown in Fig. 6; Fig. 7, a detail view in elevation of a part of a clutch-supporting starter shaft, and showing the rack and pinion mechanism and starter shaft in the position which they would occupy when the main clutch members are in clutching

engagement,—the bottom rack for moving the starter endwise being shown in full lines at one extremity of its movement; and Fig. 8, a view in elevation of a portion of a motor vehicle provided with an engine starting device constructed in accordance with my invention and improvements.

In constructing an engine starting device in accordance with my invention and improvements, I provide a starter shaft *a* which is rotatably mounted in a suitable support comprising a stationary, preferably tubular, casing *b*, mounted in or forming a part of a stationary frame comprising a transverse frame member *c* and oblique or longitudinal side frame-members or braces *d*. The side frame members or braces *d* here shown are connected at one end of the device by means of an integral transverse frame portion *e* connected with one end of the stationary tube or casing *b* and adapted to form a support for the latter, and are connected at their opposite ends by means of screws *f* or other suitable securing means with the transverse frame member *c*. The stationary tube or casing *b* and the stationary frame members connected therewith thus form a rigid frame adapted to be secured to the main frame of a vehicle by means of a supporting bracket or frame portion *g*, as indicated in Fig. 8, or by any desired ordinary and well known securing means. The starter shaft *a* is provided with a series of elongated peripheral ratchet teeth *h*, shown in Figs. 3, 4 and 6. These peripheral ratchet teeth may be and are, by preference, integral with the shaft and of sufficient length so that the longitudinal movement of the starter shaft, which is necessary in order to throw the main clutch member on the starter shaft into and out of clutching engagement with the clutch member on the engine shaft, may take place in such a manner that the pawls *i* for operating the ratchet and thereby the starter shaft may remain constantly in operative engagement with the ratchet teeth *h*. The pawls *i* for engaging and operating the ratchet teeth *h* and thereby the starter shaft *a* are mounted on the inside of the outer stationary tube *b* in a suitable rotary tubular support comprising an inner tube *k* which encircles the shaft, and a main helix or helically grooved tubular member *l* which encircles the inner tube *k*. The adjacent ends of the tubular members *k* and *l* at the inner end of the shaft *a* are secured in rigid relation to each other by means of a cap, bearing member or head *m* having an inner annular flange portion *n* interposed between the inner ends of said tubular members and adapted to hold the latter in concentric relation to each other, and in concentric relation to the outer stationary tubular member *b* and the shaft *a*. The head or end cap *m* is provided with

an endwise projecting bearing portion or trunnion *o* which is rotatably mounted in a suitable socket or recess *p* in the end cap or head *q*, which latter forms the closure for one end of the outer stationary casing or tubular member *b*. The stationary head *q* is provided with an endwise projecting portion *r* which, by preference, extends through a suitable opening in the transverse stationary frame member *e*. And a threaded bearing pin or screw *s* mounted in threaded engagement with the stationary head or member *q*, forms a suitable end bearing for the trunnion or bearing portion *o* of the head *m*, and a lock nut *t* serves to hold the bearing pin or screw *s* in position. The outer casing or tubular member *b* is secured to the head *q* by means of screws *u* or other ordinary suitable securing means. A cap or collar *v* encircles the shaft *a* at the opposite end of the inner tubular members *k* and *l* and is removably secured in fixed relation to the rotary tubular member *l* by means of studs or pins *w*, as shown in Figs. 3 and 4, or by other suitable securing means. A stationary collar *y* encircles the shaft *a* on the outside of the collar *v* and is secured in rigid relation to the end of the tube *b* by means of screws *z*, said collar *y* being provided with a suitable annular groove or ball race 2 into which projects an annular flange portion 3 of the collar *v*, said groove 2 and flange portion 3 being adapted to form therebetween a ball race in which are located hardened steel balls 4 which form a ball bearing between the collars *y* and *v*.

From the foregoing it will be seen that the tubular members *k* and *l* are prevented from moving endwise and are rotatably supported between the stationary bearing or head *q* at one end of the device and the collar or cap *y* at the other end, and that a rotary tubular frame or support for the pawls *i* is thus provided which is adapted to operate the pawls *i* when the tubular frame or helically grooved member *l* and tube *k* are rotated together. The pawls *i* above mentioned are pivotally supported in suitable pockets or sockets *s* in the enlarged end portion 6 of the inner tubular member *k* and are held in position to operatively engage the ratchet teeth *h*, already described, by means of the end collar or head *v* which forms a closure for the spirally grooved tube *l* and inner tube *k* and rigidly connects the ends of the tubular members *k* and *l* within which the pawls *i* are mounted. The pawls are thus constantly in position to engage the ratchet teeth *h* to the shaft *a*, as already suggested. The pawls *i* are yieldingly held in engagement with the ratchet teeth *h* by means of compressible springs 7, shown in Fig. 6, said springs being held in place by the tubular member *l* which is provided with suitable apertures for containing said springs and 125

for holding them in operative engagement. (See Fig. 6.)

In order to provide suitable means for rotating the tubular members *l* and *k* and thereby operating the pawls *i* to rotate the shaft *a*, the member *l* is provided with opposite peripheral helical or spiral grooves or slots *8*, and the stationary outer tube or casing member *b* is provided with longitudinally disposed, preferably straight grooves or slots *9*, which extend from end to end of the helical or spiral slots *8*. A sleeve or sliding frame *10* is mounted upon or in position to encircle the stationary outer tube *b* and is adapted to slide longitudinally of the latter when operated by the main operating lever *11* hereinafter more particularly described. Upon this sliding frame or sleeve are mounted inwardly projecting fingers, each of which, by preference, comprises a threaded pin or screw *12* mounted in threaded engagement with the sleeve *10* and having a non-threaded inner end portion *13* which projects into the corresponding slot or groove *9* and spiral or helical groove *8*. An anti-friction sleeve *14* upon each pin or finger *12* is adapted to engage the walls of the corresponding groove *9* in the stationary member *b*, and a similar anti-friction sleeve *15* for each pin *12* is adapted to engage the walls of the corresponding helical or spiral groove *8*, into which grooves said fingers and sleeves extend. The helical or spiral grooves *8* and the longitudinal grooves *9* are so disposed with relation to each other that the inwardly projecting fingers or bosses comprising the pin *12* and sleeves *14* and *15* are adapted to move from end to end of said grooves in such a manner that the movement of the fingers from the position shown in Fig. 4 to or in the direction of the position in which they are shown in Fig. 1 will cause the connected tubular members *l* and *k* and thereby the pawls *i*, ratchet teeth *h* and starter shaft *a* to rotate in the direction of the arrow, as indicated in Fig. 4, and the movement of the fingers in the opposite direction longitudinally of the casing *b* or from the position indicated in Fig. 1 to the position in which the fingers are shown in Fig. 4 will cause the main helically grooved tubular member *l* and the tube *k* and pawls *i* to rotate in the opposite direction to that indicated by the arrow in Fig. 4, but without rotating the shaft, as the ratchet teeth are inclined so as to permit freedom of movement of the pawls *i* in the last mentioned direction around the shaft *a*. From the foregoing it will be seen that the inner anti-friction sleeves *15* upon the inwardly extending pins *12* may be loosely mounted upon said pins, and that the inner tubular member *l* is adapted to prevent the sleeves from coming off the pins and to

permit the movement of the outer pin supporting sleeve or frame *10* longitudinally of the casing *b* from one extremity to the other of the spiral or helical groove *8* in the rotary helix or helically grooved tube *l*, and in the longitudinal groove *9* in the outer tube or casing *b*, and that the movement of the fingers with the finger supporting frame or sleeve *10* will cause the tubular member *l* to rotate upon the bearing *o* at one end and the ball bearings *4* at the opposite end of the rotary tubular structure comprising the connected tubular members *k* and *l*. The helical grooves *8* are, by preference, of such a pitch and so disposed that the movement of the fingers or pins *12* from end to end of the grooves *8* will cause the helically grooved tube *l* with the pawls *i* to make approximately one-half of a revolution, or more, if found desirable in practice, or, in other words, will cause the starter shaft *a* to rotate approximately one-half of a revolution or sufficiently to crank the engine or compress a charge of combustible fluid contained in the engine cylinder and bring the engine pistons into the proper position for ignition of the charge or for starting, in one direction. It is desirable to provide means whereby the shaft *a* and the clutch member supported thereby will be moved endwise into clutching position during the movement of the operating lever *11* and the slide or helix-operating fingers *12* in an opposite direction from that in which said lever, slide and helix-operating fingers are moved in operating the pawls *i* to turn the starter shaft *a* and thereby the engine shaft. It is also desirable that the device be capable of enabling the cranking or starting of the engine or the compression of the charge to be accomplished by a continuous stroke or movement of the operating lever *11* and the helix-operating fingers *12*.

The main operating lever is, by preference, pivotally connected at one end with the free end of a link *16* by means of a pivot *17* (see Figs. 4 and 6), the opposite end of the link being pivotally connected with a support such as a hinge member *18*, said hinge member being secured to the non-rotatable frame comprising parts *c* and *d*, or other suitable support, by means of screws *f*, already described, or by any desired, ordinary and well known means. The operating lever *11* is operatively connected with the sliding sleeve *10* and thereby with the inwardly projecting pins *12* by means of a yoke or frame member *20*, the opposite ends of which are provided with suitable openings through which lateral bosses *21* on the sleeve *10* extend, the bosses *21* being provided with threaded openings through which the pins *12* extend, as shown in Fig. 4. The yoke or frame member *20* is pivotally connected with the main operating le-

ver 11 by means of a pivot 22, shown in Figs. 3, 4 and 6, said yoke or U-shaped frame member being bent into or constructed in such form that it partially encircles the outer tube or casing *b* and extends from the points of connection with the sliding sleeve 10 or finger 12 in the direction of the end of the casing *b* toward which the sleeve 10 and fingers or pins 12 are moved by the lever 11 in the operation of rotating the shaft *a*, by means of the pawls *i* and the ratchet engaged thereby.

It is desirable, as already suggested, to provide means whereby the starter shaft *a* may be moved endwise from the position shown in Fig. 3 to the position shown in Fig. 4, so as to bring the clutch member 23 into clutching engagement with the mating main clutch member 24 on the engine shaft, as shown in Fig. 4, and adapted to permit the endwise movement of the starter shaft *a* with its clutch member 23 in the opposite direction, or from the position in which said parts are shown in Fig. 4 to the position in which they are shown in Fig. 3. It is also desirable to enable the starter shaft *a* and the clutch member 23 thereon to be rotated during the endwise movement of the shaft *a* which carries the clutch member 23 into clutching engagement with the clutch member 24 on the engine shaft, and even during the initial or first part of the rotary movement of the engine shaft or clutch member 24, which occurs during or immediately following the movement of the clutch member 23 into engagement with the clutch member 24. In order to enable this and other objects which will be readily apparent to those skilled in the art to be accomplished in a simple and efficient manner, the shaft *a* is provided with a toothed rack member or sleeve-shaped rack 25 secured in fixed relation thereto and comprising in its construction a series of peripheral teeth 26 which are, by preference, inclined outward and rearward and extend around the sleeve. (See Figs. 1 to 4 inclusive and Fig. 7.) A pinion 27 is rotatably mounted in a suitable supporting frame member or bracket 28 upon a journal or axle 29 with similarly shaped peripheral ratchet teeth 30 in toothed engagement with the teeth 26 of the annular rack or sleeve-shaped rack member 25. This pinion also has a series of similar ratchet teeth 31 disposed circumferentially around substantially one-half of the pinion 27 and inclined in an opposite direction to the teeth 30 and adapted to be engaged and operated by the teeth 32 of a longitudinally movable or bottom rack 33. The rack 33 is pivotally connected with a sliding operating rod 34 by means of a pivot pin 35 mounted in said rod and extending through a suitable aperture in one end of said pivoted rack 33. A compressible spring 36 mounted in the rod

34 and in yielding engagement with the free end of the pivoted rack 33 serves to hold the teeth 32 of the latter yieldingly in position to move laterally of the operating rod into and out of operative engagement with the teeth 31 of the pinion 27. The rack-operating and supporting rod 34 is connected at one end with the sliding sleeve 10 by means of a boss 37 having a threaded aperture for receiving the correspondingly threaded end of the rod 34, or by similar securing means. The rod 34, thus secured in fixed relation to the sleeve 10, is adapted to move with the latter longitudinally of the device or of the tubular casing *b*. A relatively stationary collar or sleeve 38 mounted, by preference, in position to encircle the outer tubular member or casing *b* and rigidly secured to the latter by means of threaded screws 39 (see Figs. 3 and 4) is provided with a laterally projecting portion or boss 40 having a suitable aperture therethrough in which the rod 34 is slidably mounted. The collar 38 thus forms a guide for the rod 34 adapted to hold the latter in such position that when the rod 34 and rack 33 are moved from the position shown in full lines in Fig. 7 to the position shown in Fig. 3, the teeth 32 of said rack will engage the teeth 31 of the pinion 27, and when the same movement of the rack 33 and its supporting rod 34 is continued from the position shown in Fig. 3 to the position shown in dotted lines in Fig. 7, such continuation of the movement will rotate the pinion 27 thereby moving the sleeve-shaped or annular rack member 25 and the starter shaft endwise from the position shown in Fig. 3 to the position shown in Figs. 4 and 7, or into such position that the clutch member 23 on the starter shaft will be carried into clutching engagement with the clutch member 24 which is fixed to the engine shaft. A collar 40 located on the inside of the inner tube *k* and in position to encircle the shaft *a* is fixed to said shaft by means of a screw 41, or in any ordinary and well known manner (see Figs. 3 and 4), and a collar 42 which also encircles the shaft *a* is secured in fixed relation to the rotary inner tube *k* by means of screws 43, or other suitable securing means, and a compressible spring 44 is mounted between and in engagement with these collars and in position to encircle the shaft on the inside of the inner tube *k*. It will thus be seen that the endwise movement of the starter shaft *a* with its clutch member 23 from the position shown in Fig. 3 to the position shown in Figs. 4 and 7, or into a position to bring the main clutch members 23 and 24 into clutching engagement, will compress the spring 44 and that the latter will have a tendency to facilitate or accomplish the endwise movement of the shaft *a* with its clutch member 23 in an op-

posite direction or out of operative engagement with the engine shaft when the engine starts, or when the main clutch members are released or forced apart.

It will be readily understood by those skilled in the art that unless the starter shaft *a* and clutch member 23 are caused to rotate during the movement of said clutch member into clutching engagement with the clutch member on the engine shaft, there would be more or less lost motion, before the teeth 45 would come into complete or perfect clutching engagement with the pin or tooth-engaging portion 46 of the mating clutch member 24. It is therefore very desirable to provide means whereby the starter shaft *a* and the clutch member 23 will be rotated during the endwise movement of the shaft *a* which brings the clutch member 23 in clutching engagement with the clutch member 24 on the engine shaft, and whereby such rotary movement of the starter shaft *a* and clutch member 24 may be continued after such endwise movement of the shaft *a* is completed or during the initial rotary movement of the engine shaft and before the movement of the sliding frame or sleeve 10 with the inwardly projecting fingers or pins 12 in an opposite direction endwise of the casing for rotating the pawls *i* and thereby the shaft *a* is begun. In order to provide means whereby this may be accomplished in a simple and efficient manner, an inner helically grooved sleeve or helix 47 is rotatably mounted on the inside of the inner tube *k* in position to encircle the shaft *a* between the collar 40 and the inner end of the shaft (see Figs. 3 and 4), and is provided with opposite peripheral helical grooves 48 which wind around the shaft *a* or sleeve 47 in a direction opposite that of the helical grooves 8 in the larger or main helically grooved tube *l*, already described. (See Figs. 1 to 4 inclusive.). The laterally projecting pins or fingers 49 upon and in fixed relation to the rotary starter shaft *a* extend into these helical or spiral grooves 48 and are adapted to move longitudinally of the grooves from end to end thereof as the shaft *a* is moved endwise in either direction or into and out of clutching position, as already described. A non-rotatable toothed ratchet prevents the rotation of the helically grooved sleeve 47 in one direction and permits the rotation of the same in an opposite direction. This ratchet or clutch member 50 encircles the shaft *a* at a point between the inner helically grooved sleeve 47 and the collar 40 on the shaft *a* and is secured in rigid relation to the inner tube *k* by means of screws 51 or other suitable securing means, (see Figs. 3 and 4) and is provided with ratchet teeth 52 adapted to engage similar ratchet teeth 53 on the inner helically grooved sleeve 47. The rotation of

the sleeve or helix 47 in an opposite direction to that in which the starter shaft *a* is rotated during its movement into clutching position or into operative engagement with the engine shaft and while rotating the engine shaft is thus prevented, and the free rotation of the helically grooved sleeve 47 in an opposite direction during the movement of the starter shaft *a* with its clutch member out of clutching position or from the position in which the parts are shown in Fig. 4 to the position in which they are shown in Fig. 7 is permitted. A compressible spring 54 is interposed between the end cap or head *m* and the adjacent end of the helically grooved sleeve 47 so as to yieldingly hold the ratchet teeth of the sleeve 47 in toothed engagement with the teeth of the clutch member 50, in such a manner as to permit the rotation of the helically grooved member 47 in one direction with respect to the clutch member 50 which is fixed to the tubular member *k*, said member *k* being fixed to the helically grooved member *l* as herein elsewhere set forth. The free end of the main operating lever 11 is operatively connected with a manually operable lever 55 by means of a connecting rod 56. One end of this rod is connected with the operating lever 11 by means of a pin 57, or other suitable connecting means, and the other end is connected with the lever 55 by means of a pin 58 extending through suitable apertures in the connecting rod 56 and lever 55, respectively. The operating lever 55 may be in the form of a foot lever or a hand lever and is pivotally supported in a suitable stationary support or part of the frame of the motor vehicle 59 by means of a pivot pin 60 (see Fig. 8) in position to be operated by the driver or operator from the seat 61. (See Fig. 8.)

In practice the direction of movement of a foot lever for operating the main operating lever 11 and the starter device above described should be, by preference, opposite to the direction of movement of the hand lever, constructed as indicated in the drawings for the same purpose, and it will be readily understood by those skilled in the art that the main operating lever 11 is adapted to be connected with any suitable means for operating the same, which means may consist of a foot lever or hand lever or of any desired form of operating means, and the sliding support for the fingers 12 or the lever 11 may be connected with such operating means in any desirable, ordinary or well known manner.

The possibility of injury to the parts of the device or to the operator by a reverse movement of the engine shaft resulting from back firing is prevented by providing a yielding connection between the clutch member 23 and the shaft *a*, such as is afford-

70

ed by the spring *a'* shown in Fig. 3, encircling the shaft *a* and connected at one end with a sleeve 23' which is fixed to or connected with the clutch member 23 and rotatable on the shaft, the opposite end of the spring being connected with the shaft *a*. The spring should be of sufficient strength to enable the engine shaft to be rotated by the power applied through the medium of the shaft *a* and the spring and connected parts.

In operation, assuming the device to be in the position shown in Fig. 3, the sliding frame or sleeve 10 with the inwardly projecting pins or fingers 12 will be moved from the position shown in Fig. 3 to the position shown in Figs. 2 and 4. During such movement the bottom toothed rack 33 will be moved with the rod 34 and sleeve 10 from the position shown in Fig. 3 to the position shown in Fig. 2 and in dotted lines in Fig. 7, thereby rotating the toothed pinion 27 and causing the latter to move the sleeve-shaped toothed rack 26 and with it the starter shaft *a* from the position shown in Fig. 3 to the position shown in Fig. 4. During this movement of the starter shaft *a*, it will be readily seen that the laterally projecting pins 49 on the shaft *a* and which extend into the helical grooves 48 of the sleeve 47, as shown in Figs. 3 and 4, will travel along the spiral grooves 48 in the direction of the longitudinal movement of the starter shaft *a* as the latter moves toward the engine shaft or toward clutching position, although the direction of movement of the sleeve 10 and outer or inwardly projecting fingers 12, which engage grooves 9 in the non-rotatable casing *b*, and helical grooves 8 in the main helically grooved tube *l*, is in the opposite direction—that is to say, endwise of the casing *b* from the position in which the sleeve 10 is shown in Fig. 3 to the position in which said sleeve and the inwardly projecting fingers supported thereby are shown in Fig. 4. The shaft *a* is thus caused to rotate in a direction corresponding with the direction of movement of the laterally projecting pins 49 in the approximately stationary spiral grooves 48, the spiral or helical grooves 47 being held against rotation by means of the clutch member 50 and the fingers 12 on the non-rotatable sliding sleeve or frame 10. The teeth 26 of the sleeve-shaped rack member 25 on the starter shaft *a* being so formed as to extend entirely around the shaft or sleeve, it will be readily seen that the above mentioned rotary movement of the shaft *a* during its longitudinal movement toward clutching position is permitted and will not interfere with the operation of the rack 25 by means of the pinion 27 and the longitudinally movable rack 33. It will also be readily seen that on account of the ratchet

teeth *h* on the starter shaft *a* being of sufficient length so that they will at all times be in operative engagement with the pawls *i*, which are supported by the rotary tubular members *k* and *l*, the teeth *h* will at all times be in position to be engaged by the pawls *i*, and that the pawls *i* and the rotary tubular pawl-supporting members *k* and *l* cannot move circumferentially of the shaft except when the spirally grooved tubular member *l* is being rotated by the movement of the helix-operating fingers 12 longitudinally of the casing *b* with the sliding sleeve or support 10. The fingers 12 when stationary prevent the rotation of the helically grooved tubular member *l* and hold the pawls *i*, as well as the ratchet member or inner clutch member 50 on the tubular member *k*, against rotation. It follows that the pawls *i* and ratchet teeth *h* are in position to prevent the rotation of the starter shaft *a* in one direction or in a backward direction and to cause the rotation of the starter shaft in the direction in which the pawls *i* are rotated in order to crank the engine or rotate the engine shaft in the operation of starting the engine. The movement of the lever 11 and sliding frame or sleeve 10 with the inwardly projecting helix-operating fingers 12 from the position shown in Fig. 3 to the position shown in Fig. 4, as above described, will cause the starter shaft and the main clutch member 23 to be moved from the position shown in Fig. 3 to the position shown in Fig. 4 or into such position that the clutch members 23 and 24 are in clutching engagement, as above suggested. When the parts have thus reached the position shown in Figs. 2 and 4, the movement of the lever 11 in the opposite direction or from the position in which it is shown in Fig. 4 to the position in which it is shown in Fig. 1 will cause the inwardly projecting fingers or pins 12 to move longitudinally of the outer casing *b* from end to end of the corresponding slots 9 and from end to end of the helical grooves or slots 8 in the larger helically grooved tubular member *l*, thus causing the starter shaft *a* to be rotated by means of the action of the pins 12 upon the helically grooved tubular member *l* in the direction indicated by the arrow in Fig. 4, thereby rotating the pawls *i* and causing the rotation of the engine shaft approximately one-half of a complete revolution or to an extent corresponding with the relative positions of the opposite ends of the spiral grooves 8. The main operating lever 11 having thus reached the position shown in Fig. 1, it will be readily seen that its movement in a reverse direction from that last described or from the position shown in Fig. 1 to the position shown in Fig. 4 will cause the rack 33 to engage and again operate the pinion 27 and thereby

130

the sleeve-shaped rack 25 during the latter part of such movement of the lever, and will thus cause the clutch members 23 and 24 to be again brought into clutching engagement in the manner already described, and that the clutch members will be brought into engagement and permitted to become disengaged with each complete cycle or operation of the main operating lever, as above described.

The movement of the starter shaft *a* from clutching position to the opposite extremity of its movement or to the position shown in Fig. 3 will cause the inner helically grooved sleeve 47 to make a partial rotation which is permitted by the spring at the end of said inner helically grooved sleeve. As the sleeve is rotated by the laterally projecting pins 49 on the shaft *a*, and which pins extend into the helical groove in said sleeve and move with the shaft *a*, the spring permits the inner helix or sleeve 47 to rotate in one direction with respect to the clutch member 50 which is fixed to and adapted to rotate with the tubular members *k* and *l*. Locking of the parts in a manner which would interfere with the successful operation of the device is thus prevented.

I claim:

1. In a device for starting engines of motor vehicles, the combination of a rotative starter shaft, means for supporting the starter shaft, an engine shaft, clutch mechanism adapted to form a connection between the starter shaft and such engine shaft, reciprocating operating lever mechanism, a rotary element encircling and rotative with respect to the starter shaft and provided with a peripheral helical portion, means operatively connected with said operating lever mechanism and extending into engagement with and movable longitudinally of said helical peripheral portion of said rotary shaft-encircling element, and means for operatively connecting the rotary shaft-encircling element with the shaft.

2. In a device for starting engines of motor vehicles, the combination of a rotative starter shaft, means for supporting the starter shaft, an engine shaft, connecting clutch mechanism adapted to form a connection between the starter shaft and such engine shaft, a main operating lever, a rotary sleeve encircling the starter shaft and provided with a peripheral helical portion, reciprocating sleeve-engaging mechanism connected with said operating lever and extending into engagement with the helical peripheral portion of said sleeve, and means for operatively connecting the sleeve with the starter shaft.

3. In a device for starting engines of motor vehicles, the combination of a rotative starter shaft, means for rotatably supporting the starter shaft, an engine shaft, con-

nnecting clutch mechanism adapted to form a connection between the starter shaft and such engine shaft, a main operating lever, a rotary sleeve encircling the starter shaft and provided with a peripheral helical portion, reciprocating sleeve-engaging mechanism connected with said operating lever mechanism and extending into engagement with the helical peripheral portion of said sleeve, means for operatively connecting the sleeve with the starter shaft, and means for moving the clutch member of the starter shaft into position, to connect the starter shaft with the engine shaft during rotary movement of said starter shaft.

4. In a device for starting engines of motor vehicles, the combination of a rotative starter shaft, means for supporting the starter shaft, an engine shaft, connecting clutch mechanism adapted to form a connection between the starter shaft and such engine shaft, operating lever mechanism supported independently of the starter shaft, a rotary sleeve encircling and rotative with respect to the starter shaft and provided with a peripheral helically grooved portion, means connected with the lever mechanism and in engagement with the helically grooved portion of said sleeve for rotating the sleeve, and pawl and ratchet mechanism upon and adapted to form a connection between the helically grooved sleeve and the starter shaft.

5. In a device for starting engines for motor vehicles, the combination of a rotary shaft, an engine shaft, means for operatively connecting said shaft with such engine shaft, a main operating lever, a sleeve mounted in rotative relation to and encircling the rotary shaft, said sleeve being provided with a peripheral helical groove, a non-rotative tubular member encircling said sleeve and provided with a longitudinal slot adjacent to the helically grooved portion of said rotative sleeve, a sleeve-operating member connected with said lever and having a sleeve-engaging portion extending through the slot in the non-rotative tubular member and in engagement with the helical groove of said sleeve, and pawl and ratchet mechanism upon and adapted to form a connection between said rotative helically grooved sleeve and said rotative shaft.

6. In a device for starting engines of motor vehicles, the combination of a rotary starter shaft, an engine shaft, means for removably connecting said shaft in operative engagement with such engine shaft, a main operating lever, a sleeve rotatively mounted and encircling the starter shaft, said sleeve being provided with a peripheral helically grooved portion, a sleeve-operating member connected with said lever and having a sleeve-engaging finger in engagement with a helical groove of said ro-

- 5 tative sleeve, pawl, and ratchet mechanism upon and adapted to form a connection between said sleeve and said rotative starter shaft, a non-rotative tubular member encircling the rotative helically grooved sleeve and provided with longitudinal slots on opposite sides of said sleeve, a collar encircling the non-rotative tubular member and in supporting engagement with 10 said groove-engaging finger, and guiding mechanism extending longitudinally of and in parallel relation to the non-rotatable tubular member, for guiding said collar and 15 70
7. In a device for starting engines of motor vehicles, the combination of a rotative starter shaft, means for supporting the starter shaft, an engine shaft, connecting clutch mechanism secured to and rotatable with the starter shaft and adapted to form 20 75
- 20 a connection between the starter shaft and such engine shaft, operating lever mechanism supported independently of the starter shaft, pawl and ratchet mechanism for rotating the starter shaft, a rotary element in 25 supporting engagement with the pawl mechanism and rotative with respect to and encircling the starter shaft and provided with a peripheral helical portion, means operatively connected with said operating lever mechanism and extending into engagement with and movable longitudinally of 30 80
- 30 said helical portion of said rotary shaft-encircling element, for rotating the pawl mechanism, and means for moving the 35 85
- 35 starter shaft endwise into position to bring said starter shaft into operative connection with the engine shaft during the rotary movement of said starter shaft. 90
8. In a device for starting engines of motor vehicles, the combination of a rotary starter shaft, an engine shaft, a clutch member connected with the starter shaft, and movable with the latter into and out of position to engage a mating clutch member on 40 95
- 40 such engine shaft, a main operating lever, shaft-operating mechanism operatively connected with the main operating lever and with the starter shaft, for rotating the latter, rack teeth upon the starter shaft, a 45 100
- 50 toothed pinion rotatively mounted in toothed engagement with said rack teeth, a longitudinally movable toothed rack adapted to engage said pinion, and means connected with the main operating lever, for 55 105
- 55 operating said longitudinally movable rack, to cause endwise movement of the starter shaft. 110
9. In a device for starting engines of motor vehicles, the combination of a rotary starter shaft, an engine shaft, a clutch member connected with the starter shaft and movable with the latter into and out of position to engage a mating clutch member on 60 115
- 60 such engine shaft, a main operating lever, a sleeve encircling the shaft and provided 65 120
- 65 with a helical peripheral groove, a laterally projecting pin on the shaft and extending into the helical groove, said pin being movable with the shaft and along said groove in a direction lengthwise of the sleeve, means 70 125
- 70 for limiting the movement of the sleeve in a direction opposite to the direction of rotation of the shaft, and means operatively connected with the main operating lever for moving the shaft endwise into position to 75 130
- 75 support the clutch member on the shaft in clutching position, said last mentioned means being adapted to permit the rotation of the shaft during said endwise movement. 80
10. In a device for starting engines of the class described, the combination of a rotary starter shaft, an engine shaft, a clutch member connected with the starter shaft and movable with the latter into and out of position to engage a mating clutch member on 85 90
- 85 such engine shaft, a main operating lever, a sleeve encircling the shaft and provided with a helical peripheral groove, a laterally projecting pin on the shaft and extending into the helical groove, said pin being movable with the shaft lengthwise of the sleeve and along said groove, a clutch member mounted upon a suitable support and in engagement with said sleeve, said clutch member being adapted to limit the movement of 95 100
- 95 the sleeve in one direction and permit the rotation of the sleeve in an opposite direction, means for yieldingly holding said sleeve and said clutch member in engagement with each other, a series of rack teeth on the shaft, a pinion in toothed engagement with said rack teeth, means for rotatably supporting said pinion, a longitudinally movable toothed rack in toothed engagement with said pinion, and rack operating mechanism connected with the longitudinally movable pinion-operating rack and with the main operating lever, for operating the rack and pinion mechanism to move the shaft longitudinally into position 100 105
- 100 to permit the engagement of the clutch member on said shaft with a mating clutch member. 110
11. In a device for starting an engine of the class described, the combination of a rotary starter shaft, an engine shaft, a clutch member connected with the starter shaft and movable with the latter into and out of position to engage a mating clutch member on 115 120
- 115 such engine shaft, a main operating lever, a sleeve encircling the shaft and provided with a helical peripheral groove, a laterally projecting pin on the shaft and extending into said helical groove, said pin being movable with the shaft lengthwise of the sleeve 125 130
- 120 and along said groove, a clutch member mounted upon a suitable support and in engagement with said sleeve, said clutch member being adapted to limit the movement of the sleeve in one direction and to permit the 130

- rotation of the sleeve in an opposite direction, means for moving the shaft longitudinally in one direction, said means being operatively connected with the operating lever and adapted to permit the rotation of the shaft during such endwise movement, and means for moving the shaft endwise in an opposite direction.
12. In a device for starting engines, the combination of a rotative starter shaft, means for supporting and permitting the endwise movement of the starter shaft, a clutch member connected with said shaft and movable with the latter into and out of position to engage a mating clutch member on an engine shaft, a main operating lever, pawl and ratchet mechanism in operative engagement with said shaft, a rotary tubular member encircling the shaft and in supporting engagement with the pawl mechanism, said rotary tubular member being provided with peripheral helical grooves, a stationary tubular casing member provided with longitudinal peripheral grooves adjacent to the helical grooves of the rotary helically grooved tubular member, operating fingers operatively connected with the operating lever and extending into said grooves in the stationary casing member and into the corresponding helical grooves in the rotary helically grooved pawl-supporting member, means for limiting the endwise movement of the rotary helically grooved member, and means for supporting the main operating lever.
13. In a device for starting engines, the combination of a rotative starter shaft,
- means for supporting the starter shaft, a main operating lever, means operatively connected with the main operating lever for moving the starter shaft endwise in one direction and adapted to permit the endwise movement of said shaft in an opposite direction, a clutch member connected with said shaft and movable with the latter into and out of position to engage a mating clutch member on an engine shaft, pawl and ratchet mechanism in operative engagement with said shaft, a rotary tubular member mounted in suitable bearings in position to encircle the shaft, and in supporting engagement with the pawl mechanism, and provided with peripheral helical grooves, a stationary tubular casing member provided with longitudinal peripheral slots adjacent to the helical grooves of the helically grooved member, a non-rotatable sliding sleeve connected with the operating lever and movable longitudinally of the tubular casing and shaft and provided with inwardly projecting fingers extending into the longitudinal slots of the stationary tubular member and into the corresponding helical grooves of the rotary grooved member, and means for supporting the operating lever.
- In testimony, that I claim the foregoing as my invention I affix my signature in the presence of two witnesses, this 14th day of July, A. D. 1913.

SIDNEY A. MYERS.
